UNITED STATES PATENT OFFICE.

DANTE A. RAGGIO, OF CHICAGO, ILLINOIS.

LOCKING MEANS.

1,421,563.

Specification of Letters Patent. Patented July 4, 1922.

Application filed January 11, 1919. Serial No. 270,636.

To all whom it may concern:

Be it known that I, DANTE A. RAGGIO, a citizen of the United States, residing at Chicago, in the county of Cook and State of Illinois, have invented certain new and useful Improvements in Locking Means, of which the following is a specification.

This invention relates to locking means, and more particularly to means for locking 10 the drawers or other parts of desks in closed position.

Among the objects of my invention is to make possible a positive and secure locking means which will eliminate any undesirable 15 abrasion or cutting into the material of which the drawer or other part being locked is formed; further to provide a hook stamped out of a single piece of metal and formed with a bearing flange at its free 20 or locking end whereby said end will more freely and readily ride to its locking position over the edge of the desk drawer or part being locked; further to extend said flange to the bottom of the recess forming 25 the holding portion of the hook, whereby to increase the bearing surface, easy operation and effectiveness of the hook; further to provide a hook that can be quickly stamped out in large numbers and capable of 30 being readily assembled in operative position; further to make possible a more simple, efficacious and economical device of the class described; and such further objects, advantages, and capabilities as will later 35 more fully appear.

My invention further resides in the combination, construction and arrangement of parts illustrated in the accompanying drawing, and while I have illustrated therein a 40 preferred embodiment of my invention, I desire it to be understood that the same is susceptible of modification and change without departing from the spirit of my invention.

45 In the drawing:

Fig. 1 is a perspective view of the rear portion of a desk drawer with my improved locking means shown in locking engagement therewith in full lines, and in released position in dotted lines.

50 Fig. 2 is a side elevation of my improved hook or latch.

Fig. 3 is a plan view of Fig. 2.

Referring to the drawings 1 designates 55 a desk drawer (usually formed of wood)

slidably mounted in the usual guideways 2 and 3, and provided with the vertical rear wall 4. It is, of course, to be understood that my invention is not limited merely to the locking of drawers, but it may be utilized for locking any member or members for which it may be adapted. The drawer here described is for use in desks of the well known type in which when all the drawers but one are pushed shut, they will be locked 60 upon pushing into closed position the said remaining one. Also if all or some of the drawers except said one are open, the pushing in of any or all of the open drawers will cause a hook to seat itself in locking engagement with the drawer in question and hold the same locked until the said one is opened. Since this type of desk is so well known, it is thought unnecessary to fully 65 illustrate the details of the same in the drawing further than to show one of several possible forms, the one chosen having fixed vertical upright member 5 and a vertically movable upright member 6 (the vertical movement being indicated by dotted lines in 70 Fig. 1), this member 6 being normally held (by a spring or otherwise, in a manner well known in the art) in its upper position and being forced against said spring to its lower 75 position when a certain drawer is moved to 80 closed position.

Pivoted at 7 to the fixed vertical member 5 is my improved hook 8, which also has pivotal connection at 9 with the vertically movable member 6. This hook is provided 90 in its lower edge with a recess 10, the metal defining which recess is curved as shown at 11 at the rear end of the recess and is substantially vertical at the forward end of the recess as shown at 12 in Fig. 2. The body 95 of the hook is formed with apertures 13 and 14 to provide for the pivotal mountings 7 and 9. At its forward lower edge the hook is formed with a bent over flange 17 forming the widened cam surface 15 extending from 100 the forward edge of the recess to the forward end of the hook, and at its forward upper edge with the curved portion 16. The curved portion 16 may under certain conditions be omitted if desired and the top edge 105 of the hook be straight.

The hook is preferably formed by being stamped from a single piece of metal and during the stamping operation the rectangularly projecting flange 17 is formed to extend 110

along the full length of the cam 15 and vertically at 18 (as the hook stands in Fig. 2) along the front edge of the recess to the full depth of the recess.

- 5 In operation, it will be seen that when a given drawer is closed as described above, and the drawer 1 (which is one of the remaining open drawers) is pushed to closed position, the cam surface 15 with its extending lip or flange 17 will engage and ride over the edge of the drawer and when the drawer reaches closed position the recess 10 will snap over said edge.
- Opening of the said given drawer will permit the vertical member 6 to move under action of its spring or other actuating means (not shown but well understood in the art), to move the hooks clear of the drawers and release the same. By providing the rectangular projecting flange or lip 17, the hook not only has at this portion an extended bearing portion to give an easier, smoother and more steady movement over the edge or other portion of the drawer, but it eliminates any cutting into or wearing away of the wood at the engaged portion of the drawer. By extending this flange or lip to form the vertical lip 18 there is provided a wider surface to bear against the drawer to hold it locked which again eliminates cutting or biting into the wood and gives a more positive lock, and at the same time, due to the wider bearing surface, the hook will more readily slide over the wood when the hook is being elevated to releasing position. It will be noted that the flange or lip 17 is integral with the flange or lip 18, and this forms one continuous unbroken surface all along the cam surface and the front edge 40 of the recess in the hook. This not only strengthens the locking portion of the hook, but it also provides a rounded shoulder at the point of joining of the flanges 17 and 18. Were the flanges 17 and 18 omitted the hook would in a short while so abrade or bite into the material of the drawer that its operation would become a source of much annoyance and the hook soon lose

its efficiency. By my invention, it is therefore readily seen that a much more freely acting and positive hook is produced, and which also embodies the further advantage of being simple and cheap to manufacture due to their being adapted to be quickly stamped in large quantities from metal by dies whereby all of the hooks will be exact duplicates.

While I have illustrated and described my hook in connection with a desk having the stationary part 5 and the movable part 6, it is readily understood to those skilled in the art that the operation of the hook may be effected in other manner and the hook made to engage other parts of the drawer than the upper edge. I wish it to be understood, therefore, that I contemplate the use of my improved hook in all ways for which it may be adapted, and be operated by such release means as may be provided.

Having now described my invention, I claim:

A desk hook stamped from sheet metal and adapted for use with wooden or other soft material drawers, said hook comprising a strong light-weight body portion having a notch or recess in the lower edge thereof adapted to engage and lock the drawer, the forward end of said hook being cam shaped to ride over the edge of the drawer, a portion of the sheet metal forming said hook being bent laterally at substantially right angles to the body thereof to form an integral continuous flange extending along the drawer engaging edge of the cam and the forward portion of the notch or recess forming the hook, thereby providing a light-weight hook having a continuous wide bearing surface adapted to engage the drawer.

In witness whereof, I hereunto subscribe my name to this specification in the presence of two witnesses.

DANTE A. RAGGIO.
